BOILER

Ashur U. Wetherbee, Evanston, Ill.

Application October 7, 1926, Serial No. 139,978
Renewed September 17, 1932

6 Claims. (Cl. 122—331)

This invention relates to boilers, and more particularly to a boiler for generating steam of the water tube type.

In boilers of this general class it is known to provide a plurality of steam and water drums at the upper portion of the boiler connected together by circulating tubes. These drums are connected by a plurality of sets of water tubes to a lower water drum which, in turn, is connected to a mud drum. These tubes are heated by means of a suitable furnace including a setting enclosing the sets of tubes and drums. It is necessary in this construction, to obtain sufficient heating surface, to employ a large number of tubes. This, together with the necessary setting, renders the construction and setting of the boiler expensive from the standpoint of time and labor as well as the cost of materials.

Another objectionable feature to the general type of horizontal multi-tubular water tube boilers commonly used is the difficulty of obtaining uniform and rapid circulation of the water. This is due, to a large extent, to the large number of tubes necessarily employed and the various connections between these different sets of tubes and the various drums. These numerous connections necessarily impede the flow of the water and materially interfere with that rapid and uniform circulation which is so very desirable in a steam boiler.

I have found that the above objections can be overcome by using a single set of tubes establishing direct communication between the mud drum and the water and steam drum, and forming parts of the boiler to provide supporting structures for the boiler as well as water legs and a water jacket enclosing the fire-box and combustion chamber. This avoids the necessity of an expensive setting and also provides an unusually large heating surface. The provision of a large combustion chamber and large heating surface insures complete combustion and also insures that the greater portion of the heat will be extracted from the hot gases and products of combustion flowing through the furnace, resulting in high operating efficiency. A furnace constructed in this manner occupies minimum space for a given capacity and is easily adaptable to available space, both of which are important considerations in installing boilers.

One of the main objects of the invention is to provide a steam boiler of simple and comparatively inexpensive construction and high efficiency. A further object is to provide a boiler in which a part of the enclosing casing is utilized

as a water jacket enclosing the fire-box and combustion chamber, the water jacket and part of the casing also constituting a leg for the circulation of the heated water. A further object is to so position the water jacket and portions of the casing relative to the fire-box and combustion chamber that the water flowing downwardly through the legs will absorb a large part of the heat from the heated gases and products of combustion passing through the furnace so as to be preheated thereby, thus utilizing this heat, which in furnaces of ordinary construction goes up the chimney. Further objects will appear from the detailed description.

In the drawings:—

Figure 1 is a longitudinal vertical sectional view through a boiler constructed in accordance with my invention;

Figure 2 is a section taken substantially on line 2—2 of Figure 1;

Figure 3 is a section taken substantially on line 3—3 of Figure 1;

Figure 4 is a section taken substantially on line 4—4 of Figure 1;

Figure 5 is a longitudinal vertical sectional view through a modified form of the boiler;

Figure 6 is a vertical longitudinal sectional view through another modified form;

Figure 7 is a section taken substantially on line 7—7 of Figure 6;

Figure 8 is a longitudinal vertical sectional view through another modified form of the boiler; and

Figure 9 is a section taken substantially on line 9—9 of Figure 8.

The furnace includes a main casing 1 of sheet metal which is suitably braced and stayed in a known manner. This casing is of approximately rectangular shape longitudinally and transversely and has mounted therein a grate structure 2 of known type positioned between the front of the casing and a bridge wall 3 of refractory material. The front wall 1a is provided with suitable openings in which are mounted door frames 4 and doors 5, respectively, in a known manner and of known construction, the doors being positioned for insertion of fuel into the fire-box and removal of ashes from the ash pit beneath the grate. A suitable refractory lining 6 is provided above the fire-box door and a water gauge 7 of known construction is connected to the steam and water space in the usual manner. The side walls of the casing are formed of inner and outer walls 7a and 8, respectively, which are spaced apart to provide steam and water spaces 9. The

spaces 9 are closed at the upper and lower ends thereof by top and bottom plates 10 and 11, respectively, which are formed by bending wall 7a outwardly and are secured to wall 8 by welding, riveting, or in any other suitable or preferred manner. The plates 7a and 8 and associated parts constitute water legs which, due to their hollow construction, possess very appreciable mechanical strength and serve to support the casing 10 1 at the sides thereof. These water legs extend throughout the length of the fire-box 12 and the gas passage 13, so that the products of combustion and heated gases flowing through the furnace come into contact with the inner faces of 15 plates 7a, and a large portion of the heat of these products is absorbed by the water in the water legs which is thus preheated thereby before entry of the water into the mud drum.

A mud drum 14 extends transversely of casing 20 1 at the lower end of the legs thereof adjacent a back wall 15 of refractory material. The end portions of this drum extend through the water legs and have direct communication therewith at 25 16. The drum 14 is connected by a plurality of water tubes 17, which form the "risers" of the boiler, to a water and steam drum 18 supported transversely of the casing and adjacent the top of the front thereof. The ends of this drum also extend through the water legs and have direct 30 communication therewith by means of suitable openings 19 in both the upper and lower portions of the drum. This drum is provided with a suitable safety valve 20 of known construction, and both of the drums are provided with suitable 35 clean out openings and means for closing the same. A steam take off pipe 21 extends transversely of the casing in back of the back wall 22 thereof and has direct communication at its ends with the steam spaces 23 in the upper portions 40 of the water legs above the normal water level thereof, and a steam conduit 24 is connected to this pipe by a T 25.

The plate 22 extends the whole width of casing 45 1 and also extends from an upper baffle wall 26 of refractory material to the top wall of the casing, terminating adjacent a collar 27 secured to the top wall of the casing and adapted for reception of the smoke pipe or conduit for connecting the outlet opening 28 defined by the collar to a 50 chimney or stack. A suitable damper 29 is mounted adjacent collar 27 and positioned for controlling the draft by regulating the effective area of the opening 28. Plate 22 is preferably provided with a suitable clean out opening normally closed by a slide or door 30, and the casing 55 can also be provided with suitably positioned clean out openings and means for closing the same, as will be understood.

The baffle wall 26 extends completely across the 60 interior of the casing and from a point in rear of plate 22 to within a short distance of drum 18. This plate is disposed in parallelism with and closely adjacent the upper row of tubes 17 and is provided at its upper end with a depending supplemental baffle plate or nose 30 which extends 65 downwardly. This wall or nose baffle 30 is optional in the various forms of boiler herein shown. A cap plate 31 of arcuate cross section is positioned adjacent the lower end of plate or wall 26 70 and extends the full width of the casing, this cap plate fitting snugly over the rounded lower end portions of the upper row of tubes 17 and closing the space between baffle 26 and the top of the mud drum 14. Cap plate 31 is held against rearward movement by an angle strip 32 secured to 75

the top of drum 14. This cap plate may be provided with a suitable hand hold 34 to facilitate removal of the same for cleaning out between the tubes 17.

A lower baffle wall 35 of refractory material 5 extends completely across the interior of casing 1 and is disposed closely adjacent and parallel to the upper surfaces of the lowermost row of tubes 17, or some higher row, this wall extending from the lower portion of drum 18 to within a short distance of the mud drum 4. It will also be noted that the lining 6 fits snugly about the lower forward portion of the drum 18, and a closure plate 36 extends from the upper portion of the drum to the top wall of casing 1. By arranging the baffles in the manner illustrated and described, the products of combustion are caused to assume a tortuous path of travel passing beneath the baffle wall 35 and around the same, flowing upwardly through the spaces between the tubes 17 and then passing upwardly and rearwardly of casing 1 about the upper end of baffle wall 26 to the outlet opening 28. This insures that the heated gasses and products of combustion will be brought into intimate contact with the tubes 17, as well as with the inner walls of the water legs, so as to very effectually heat the water therein, thus utilizing a very appreciable amount of heat which would otherwise go up the chimney and be wasted. 20 25 30

It will also be noted that the lower portion of the drum 18 is so positioned as to be exposed to the direct heat of the fire in the fire-box 12 of the furnace so that the water therein is quickly heated to a high temperature, resulting in the 35 generation of large volumes of steam. In the operation of the boiler the feed water is supplied to the water legs by known means and, as it is relatively cool, flows downwardly through the water legs into the mud drum 14, this feed water being preheated by the products of combustion flowing through the casing 1 in the manner previously described. From the mud drum 14 this preheated water flows upwardly thru the tubes or risers 17 during passage through which 40 it is heated to a high temperature, and then enters the drum 18. In the drum 18 the water is heated to a still higher temperature and a large portion thereof is converted into steam, the remainder flowing from the drum 18 into the 45 water legs through which it flows downwardly and again enters the drum 14. As the water legs are of comparatively great cross-area, free and continuous circulation of the water is thus insured, resulting in the production of a large 50 volume of steam for a given amount of fuel consumed, thus producing a boiler of very high efficiency. 55

In the modified form illustrated in Figure 5, the smoke conduit 37 extends from the back 60 portion 33a of casing 1, and the nose baffle 30 is omitted. A supplemental bridge wall 3b of hollow construction is mounted on the main bridge wall 3a and has direct communication at its ends with the water legs; and the inner front liner 6a is also of hollow construction and has direct communication at its ends with the water legs. An inclined deflector plate 38 extends from the top wall of the casing to the smoke conduit 37 and extends completely across the casing, and an inclined back wall 39 extends from the lower portion of smoke conduit 37 to a T-bar 40, extending transversely of the casing above the mud drum 14. This T-bar serves to hold the flat cap plate 41 in position between the bar and the lower 70 75 80 85 90 95

end of baffle wall or plate 26. Bar 40 also serves to hold in position a plate 42 extending from the upper portion of the mud drum to the bar 40 and disposed adjacent the lower end of the upper 5 row of tubes 17. In this construction the path of travel of the products of combustion is slightly lengthened over the construction disclosed in Figures 1 to 4, thus obtaining an additional saving in heat which would otherwise be wasted and 10 further increasing the efficiency of the boiler.

In the form illustrated in Figures 6 and 7, I provide an upper grate 43 formed of headers 44 extending transversely of the casing and having direct communication at their ends with the 15 water legs, these headers being connected by inclined water tubes 45, and a baffle wall 46 being provided which extends from the upper portion of the inner header 44 to the lower baffle plate or wall 35. The front wall of the casing is provided with a suitable opening and an upper 20 fire-door 47 normally closing the same and permitting fuel to be placed upon the grate structure 43, and a suitable lining 48 of refractory material extends from the top of the door opening 25 above grate 43 to the drum 18. A smoke conduit 49 extends from the supplemental baffle plate 30 and the upper inner portion of drum 18 to a collar 31 on the top of casing 1 for reception of a smoke pipe or conduit by means of which the 30 smoke and the gases are conducted to a suitable stack or chimney. The walls or plates 7b and 8a of the water legs are connected by channel members 10a and 11a secured thereto by riveting, welding, or in any other suitable or preferred 35 manner.

The fuel is initially placed upon the upper grate 43 and a down draft is created through the fuel bed, the path of flow of the air and the products of combustion being indicated by the arrows. 40 This results in quickly heating the water within the grate structure 43 to a high temperature. As the fuel is coked it falls between the tubes 45 onto the grate 2 where it is completely consumed, the ash falling through the grate 2 into 45 the ash pit. It will be noted that the heated gases and products of combustion flowing through the smoke conduit 49 are caused to flow over and about the inner portion of drum 18 in direct contact therewith. The outer lower portion of the 50 drum is also subjected to the direct action of the heat generated in the upper combustion chamber 12a. This results in quickly heating the water within drum 18 to a high temperature which action, combined with the heating of the 55 water in the grate structure 43 and the free circulation of the water previously referred to, renders it possible to generate a large volume of steam with the consumption of a comparatively small amount of fuel.

60 In the modified form illustrated in Figures 8 and 9, the grate 2a is inclined downwardly and rearwardly of the casing 1, so as to be disposed in substantial parallelism with the tubes 17, and the upper and lower portions of plates or walls 8b 65 of the water legs are turned inwardly at right angles to form top and bottom closure elements 10b and 11b, respectively, which are secured to inner walls 7c by butt welding. The bridge wall 51 is extended upwardly to the lowermost row 70 of tubes 17 and has its front face 51a disposed substantially at right angles to the grate 2a. A baffle 52 extends from the upper end of bridge wall 51 to the uppermost row of tubes, this baffle 75 extending completely across the interior of casing 1 and between the tubes. A lining 53 of re-

fractory material is positioned adjacent the top of casing 1 and extends from the upper portion of drum 18 to a vertical baffle wall 54 which extends transversely of the casing above the tubes 17 and is provided with a depending angularly disposed reduced portion 55, which extends around and between the tubes, this reduced portion 55 extending to the lowermost row of the tubes. A smoke conduit 56 communicates with the casing 1 adjacent the rear face of baffle wall 54 and an inclined back plate 57 extends from the upper portion of mud drum 14 to the rearward portion of the opening 58 with which the conduit 56 communicates, the plate 57 extending completely across the interior of casing 1. In 15 this form the products of combustion from the fire chamber 12b flow upwardly around and between the tubes 17 substantially at right angles thereto and around the lower portion of drum 18 in direct contact therewith. The products of 20 combustion then flow over and about the upper portion of baffle 52 and downwardly between this baffle and baffle element 55, again reversing their direction of flow so as to pass about the lower end of baffle 55 and into the space between 25 this baffle and wall 54 and plate 57, from which space the products of combustion enter the conduit 56. By arranging the baffles in this manner the path of travel of the products of combustion is comparatively long and the direction of 30 travel of these products is completely reversed twice, so that the greater portion of the heat is extracted therefrom before the products of combustion enter the conduit 56. It is also to be noted that the baffles and the lining 53 become 35 heated to a comparatively high temperature and supplement the direct action of the products of combustion in heating the tubes and the drum 18. By thus lengthening the path of travel of the products of combustion and reversing the direction of flow thereof, it is possible to construct the 40 casing and associated parts so as to produce a boiler of much less length for a given production of steam than would be the case if the products of combustion could pass straight through the boiler from the front to the rear thereof. For this reason, a boiler constructed as illustrated in Figures 8 and 9 is particularly adapted for use where the space for installing the boiler is limited.

I also contemplate a slight modification of the form illustrated in Figures 8 and 9, in which modification the lining 53 is replaced by a cap or cover plate of refractory material disposed upon or closely adjacent the top row of tubes, and one or both of the baffles are shortened to permit flow of the products of combustion about and between the tubes. This eliminates space above the tubes and ensures that the products of combustion, while in a highly heated condition, will be brought into intimate contact with the tubes. In this respect, this variation is even more efficient than the form illustrated in Figures 8 and 9. It will also be apparent that the arrangement of closure or cover walls or linings and baffles in the other forms illustrated and described can be varied widely to suit individual preference or local conditions, and I do not, therefore, intend to be limited to the particular arrangements of baffles and wall disclosed.

In the construction shown in Figures 8 and 9 the upper and lower portions of plates or walls 8b, which constitute the dished elements of the legs, are turned inwardly. This construction can be reversed, however, the upper and lower portions of walls 7c being turned outwardly and secured 75

by butt welding to walls 8b. This variation is obvious and illustration not necessary. Either form produces a water leg of inexpensive but strong and durable construction.

5. In all of the various forms of the boiler illustrated and described, a suitable supporting base or foundation is provided with which are associated the bridge walls and the side walls 59, and the back walls for supporting the casing and associated parts.

10. Also, if desired, the boiler may be provided with a coating or covering of any suitable or preferred heat insulating material to prevent loss of heat by radiation, though I do not deem this essential due to the water jacketing effect of the water legs and the rapid and direct circulation of the water.

15. In all of the forms illustrated, the plates of the water legs are secured together at the front and back thereof in the same manner as at the top and bottom of the legs, and the water tubes are curved or arched at their ends. This is a known form of construction which permits of the tubes being connected to the drums radially thereof and also allows for expansion and contraction. This arrangement of the tubes, combined with the arched construction of the body of the boiler, produces a boiler in which ample allowance is made for expansion and contraction 20 and likelihood of weakening of parts from this cause is eliminated. The boiler may also be used for hot water heating. In that event the hot water take-off will be connected to the top of the front drum 18. The feed water may enter 25 into the boiler at any other suitable place than the water legs as, for instance, the mud drum.

30. It will be noted, that in the various forms of construction illustrated, the water legs provide large steam and water storage. I consider this 35 feature of importance as enabling the boiler to take care of fluctuating loads, which is frequently an important consideration. In all of the constructions illustrated the lower portion of the mud drum is lower than the bottom of the water legs. This ensures that all sediment will collect 40 in the portion of the boiler construction which is protected from the fire in the furnace, thus protecting the furnace wall from burning and excessive corrosion.

45. What I claim is:—

50. 1. In a boiler of the character described, a casing provided at opposite sides thereof with hollow supporting structures constituting water legs, a mud drum extending transversely of the casing adjacent one end thereof and communicating 55 at its ends with the lower portions of the water legs, a water and steam drum extending transversely of the casing adjacent the other end thereof and communicating at its ends with the upper portions of the water legs, said casing including a fire-box, and the water and steam drum being positioned above said fire-box, water tubes within the casing establishing communication between the two drums, a bridge wall at the back of the fire-box, a baffle member extending from the lower portion of the steam and water drum to within a short distance of the mud drum and disposed above the bridge wall and parallel with

and adjacent the lowermost row of tubes, an upper baffle member extending from within a short distance of the water and steam drum to within a short distance of the mud drum and disposed adjacent and parallel with the upper row of tubes, a back wall extending from the upper baffle member to the top of the casing, said casing being provided with an outlet opening adjacent the top of the back wall, and means normally closing the space between the rearward end of the upper baffle member and the upper portion of the mud drum.

5. In a boiler of the character described, a casing comprising side water legs and enclosing the boiler furnace, each of said legs comprising a 15 dished inner plate and an outer plate secured thereto, the seams at the lines of juncture between the two plates being disposed wholly without the furnace.

10. 3. In a boiler of the character described, a casing comprising side water legs and enclosing the boiler furnace, said legs constituting side supporting structures for the boiler and each comprising an inner dished plate and an outer plate secured thereto, the seams at the lines of juncture 20 between the plates of the respective water legs being disposed without the furnace.

15. 4. In a boiler construction, a casing comprising hollow side water walls, an upper header connecting and opening into the water walls, a lower header constituting a mud drum connecting the water walls, and tubes connecting said headers, the lower header extending below the lowermost points of said walls and communicating directly with the water walls through openings extending to the lowermost points thereof 25 for draining sediment from the latter into the lower header.

20. 5. In a boiler construction comprising a furnace, a casing comprising hollow side water walls, 40 an upper header connecting and opening into the water walls, a lower header constituting a mud drum connecting the water walls, and tubes connecting the headers, the lower header extending below the lowermost points of the water walls 45 and opening thereto at the lowermost points of said walls for draining sediment therefrom into the lower header, said lower header being shielded from the fire in the furnace.

25. 6. In a boiler construction, a casing, a fire box, 50 an upper header, a lower header constituting a mud drum, tubes connecting the headers, baffle means for causing the hot gases to assume a tortuous pass between and around said tubes in contact therewith, and means disposed wholly within the casing structure and connecting the adjacent sides of the headers inwardly of the ends of the respective headers and providing for downward circulation of the water, said means constituting, in effect, an extended water leg at the 55 side of the boiler and opening at its upper end into the lowermost point of the upper header, the lowermost point of said means opening into the lower header for the purpose of draining sediment from said upper header at the lowermost 60 point thereof into said lower header.

ASHUR U. WETHERBEE.
